CLAIM

The ornamental design for a shoe upper, as shown and described.

DESCRIPTION

FIG. 1 is a left side elevational view of a shoe upper showing my new design;

FIG. 2 is a right side elevational view;

FIG. 3 is a front elevational view;

FIG. 4 is a rear elevational view; and

FIG. 5 is a top plan view.

The broken line showing of a shoe sole, including the cupped vertical sides of the sole, is for illustrative purposes only and forms no part of the claimed design.

FIG. 1.

FIG. 4.

FIG. 3.

FIG. 5.
